US0D1044049S

(12) **United States Design Patent** (10) Patent No.: **US D1,044,049 S**
(45) Date of Patent: ** Sep. 24, 2024

(54) **SLAB COMPRISING PARTICULATE MINERAL MIXTURE**

(71) Applicant: **Cambria Company LLC**, Eden Prairie, MN (US)

(72) Inventors: **Jon Louis Grzeskowiak, II**, Prior Lake, MN (US); **Summer Lane Kath**, Eden Prairie, MN (US); **Martin E. Davis**, Excelsior, MN (US)

(73) Assignee: **Cambria Company LLC**, Eden Prairie, MN (US)

(**) Term: **15 Years**

(21) Appl. No.: **29/825,341**

(22) Filed: **Jan. 31, 2022**

(51) LOC (14) Cl. **25-01**

(57) **CLAIM**

The ornamental design for a slab comprising particulate mineral mixture, as shown and described.

DESCRIPTION

The sole FIGURE is a top plan view of a slab comprising particulate mineral mixture, showing our new design. The depicted surface of the slab comprising particulate mineral mixture is flat. The broken lines represent portions of the slab that form no part of the claimed design.
